INSIDE CASING CUTTER

Elton H. Leach, Lake Charles, La.

Application April 20, 1936, Serial No. 75,444

5 Claims. (Cl. 81—194)

This invention relates to pipe cutters adapted to be used for cutting off a section of piping in a well.

5 An object of the invention is to provide novel cam means for actuating the cutters.

A further object is to provide a novel means for automatically releasing the cutting means after the cutting operation has been completed.

10 A further object is to provide a device of this character which will be formed of a few strong simple and durable parts, which will be inexpensive to manufacture and which will not easily get out of order.

15 With the above and other objects in view the invention consists of certain novel details of construction and combinations of parts hereinafter fully described and claimed, it being understood that various modifications may be resorted to within the scope of the appended claims without departing from the spirit or sacrificing any of the advantages of the invention.

20 In the accompanying drawing forming part of this specification,

25 Figure 1 shows in longitudinal section, a device constructed in accordance with the invention, parts being shown in elevation.

Figure 2 is a cross sectional view taken on the line 2—2 of Figure 1 looking in the direction of the arrowheads.

30 Figure 3 is a cross sectional view taken on the line 3—3 of Figure 1 looking in the direction of the arrowheads.

35 Figure 4 is a cross sectional view taken on the line 4—4 of Figure 1 looking in the direction of the arrowheads.

40 Referring now to the drawing on which like characters of reference designate similar parts in the various views, 10 designates a tubular body having a screw thread connection 11 at the upper end with the drill pipe 12, rotation of which rotates the tubular body in its axis. The tubular body is provided at the lower end with a guide point 13 for centering the tool in the well casing to be cut, and the body is provided on the sides with tension blocks 14 which are urged radially by springs 15 behind them to engage the inner face of the well casing and coat with the point 13 in centering the tool in the well.

45 A cylindrical cam plate 16 is rotatably mounted in the lower end of the tubular body and is provided with an extension 17 which is received in a recess 18 formed in a plug 19 which closes the open bottom of the tubular body and forms means for permitting assembly of the cam plate with the tubular body and also forms means for securing the guide point to the tubular body. The cam plate is provided in the top face with preferably three spiral slots 20, best shown in Figure 4, the inner ends of which are disposed near the axis of the cam plate and the outer ends of which

open through the cylindrical wall of the cam plate. The cam plate is provided with an axial opening provided with a spiral groove 21 to receive the spirally threaded end 22 of a stem 23, the lower end of which enters a socket 24 formed in the plug 19.

50 Preferably three cutters 25, best shown in Figure 3, are slidably fitted in radial openings 26 formed in the tubular body 10 and each cutter is provided on the underneath face with a pin 27 which enters an associated spiral slot 20 on the cam plate 16. When the stem 23 is moved vertically the plate 16 will be rotated and the pins 27 will be moved longitudinally in the spiral slots 20 and carry the cutters with them according to the direction of rotation of the plate 16. Manual rotation of the plate in one direction moves the cutters outwardly to sever the well casing and rotation of the plate in a counter-direction, under impulse of a helical spring 28, withdraws the cutters to initial position.

55 The stem 23 is provided with a stop collar 29 and the helical spring 28 is confined under tension between this stop collar and an abutment 30 projecting inwardly from the bore of the tubular body. When the stem 23 is manually pulled upwardly to move the cutters outwardly, the spring will be compressed between the stop collar and the abutment and will immediately expand and withdraw the cutters when the stem 23 is uncoupled from its pulling means. A key 31 is secured in the abutment 30 by means of a screw 32 and projects into a longitudinal key-way 33 formed in the stem 23. Thus the stem is confined against rotation on its axis but may be readily moved vertically on the key to cause the threaded end 22 of the stem to rotate the cam plate clockwise and move the cutters outwardly and rotate the cam plate counter-clockwise to withdraw the cutters.

60 Referring now to Figure 1, it will be seen that a pair of latches 34 are pivoted intermediate their ends on pivot pins 35 disposed in a kerf 36 formed in the upper end of the stem 23. The lower ends of the latches are cut away obliquely to receive between them a helical spring 37 which constantly tends to urge the lower ends outwardly and consequently hold the upper ends of the latches inwardly. The upper ends of the latches are provided with hooks 38 which in normal position enter a circumferential recess 39 formed at the lower end of a stem 40, the stem being headed up as shown at 41 below the recess to provide an abutment against which the hooks bear when the stem 40 is manually pulled upward to raise the stem 23 and move the cutters 25 outwardly to operative position. A cable 42 is attached to the upper end of the stem 40, and like the drill pipe 12 is of sufficient length to reach to the top of the well so that both stems 40 and 23 may be pulled 65

upwardly as a unit while the drill pipe 12 is being rotated to simultaneously move the cutters outwardly and advance the same through a circular path to sever the pipe section in the well.

Referring now to Figure 1, it will be seen that a collar 43 is secured in the bore of the tubular body by screws 9 passed through the tubular body 10 above the lower ends of the latches. The collar is provided with a circular cam face 44 which is flared downwardly from about the center of the collar to the lower end of the collar. The lower ends of the latches are provided with cam projections 45 which, when the stem 23 is pulled upwardly, first engage the wide lower end of the cam wall 44 and ride upwardly on the wall to the narrow upper end, during which progress the hooks 38 of the latches will be gradually moved outwardly from the recesses 39 to disengage from the head 41 of the stem 40 and release the stem 40 so that it is uncoupled from the stem 23 at the time the cutters 25 reach their outermost limit of movement in performing the inside cut on the well casing. Immediately the stem 40 is uncoupled, as just described, the spring 28 expands and moves the stem 23 downwardly to simultaneously withdraw the cutters 25 and lower the latches 34, the spring 37 of the latter moving the lower ends of the latches outwardly during such lowering movement and returning the hooks 39 to position to again receive the stem 40 for a subsequent cutting operation.

The stem 40 is preferably formed on two interfitting parts as illustrated in Figure 1, connected by a frangible shear pin 46. In case of emergency where any of the parts of the tool become jammed, a quick jerk of the cable will break the shear pin and permit the cable to be removed from the drill pipe 12.

Since the operation of the device has been described as the description of the parts progressed, it is thought that the invention will be fully understood without further explanation.

What is claimed is:

1. A cutter for oil well tubing and the like comprising a rotatable tubular body, vertically movable aligned stems in the body, a head on one of the stems, spring pressed latches pivoted on the other stem and hooked over said head to couple the stems together, a projection in the body adapted to dislodge the latches from the head to uncouple the stems at a predetermined point in the upward movement of the stems, a rotary cam plate in the body having spiral grooves, radially movable cutters carried by the body and having projections fitting in said grooves, one of the stems having a spiral thread, there being a spirally threaded axial opening in the cam plate receiving the thread of said stem, and a spring on the last named stem compressed by upward movement of the stems and adapted to return the lower stem, the cam plate and the cutters to released position upon uncoupling of the stems from each other.

2. A cutter for oil well tubing and the like comprising a rotatable tubular body, vertically movable aligned stems in the body detachably connected together, means for disconnecting the stems from each other at a predetermined point in the upward movement of the stems, a rotary cam plate coaxial with the body and having spiral

grooves in the top face, radially movable cutters carried by the body and having projections fitting in said grooves, one of the stems having a spiral thread thereon, said cam plate having a spirally threaded opening receiving the thread of said stem, a key on the body engaging the last named stem for preventing rotation of the stem, and a spring on the last named stem compressed by upward movement of the stem to return the stem, the cam plate and the cutters to initial position upon the stems being disconnected from each other.

3. A cutter for oil well tubing and the like comprising a rotatable tubular body, a cable extending axially in the body, aligned upper and lower stems in the body, the upper stem being connected to the cable and having a groove in the lower end, a pair of spring pressed oppositely disposed pivoted latches on the upper end of the lower stem having their upper ends normally engaged in said groove to couple the stems together, a collar in the bore of the tubular body having a cam face flaring downwardly and outwardly, cam projections on said latches adapted to engage said cam face whereby to move the latches against the tension of their controlling spring and dislodge the latches from said groove to uncouple the stems, radially movable cutters in the tubular body, a cam member connected with said cutters for moving the cutters outwardly and inwardly, the cam member having an axial screw threaded opening, screw threads on the lower stem engaging said threaded opening, and a spring assembled with the lower stem adapted to be compressed upon upward movement of the stem for returning the stem, the cam plate and the cutters to initial position upon uncoupling of the stems from each other.

4. A cutter for oil well tubing and the like comprising a rotatable tubular body, vertically movable aligned stems in the body, means for pulling the stems as a unit upwardly in the body, a head on one of the stems, spring pressed latches pivoted on the other stem and hooked over said head to couple the stems together, a projection in the body adapted to dislodge the latches from the head to uncouple the stems at a predetermined point in the upward movement of the stems, radially disposed cutters carried by the tubular body, and means operatively connected to the cutters and to the lowermost one of the aligned stems for actuating the cutters.

5. A cutter for oil well tubing and the like comprising a rotatable tubular body, vertically movable aligned stems in the body, means for pulling the stems upwardly in the body, a head on the upper stem, spring pressed latches pivoted on the lower stem and hooked over said head to couple the stems together, a projection in the body adapted to dislodge the latches from the head to uncouple the latches at a predetermined point in the upward movement of the stems, radially disposed cutters carried by the tubular body, means operatively connected to the cutters and to the lower stem for moving the cutters outwardly when the stems are raised, and a spring cooperating with said last mentioned means for retracting the cutters after said stems have been uncoupled.
